ELEPHANT PUPPET

Juanita A. Casey and Kathleen L. Johnson, Del City,
Okla. (both of 7055 Lennox, Apt. 5, Van Nuys, Calif.
91405)

Filed Jan. 28, 1975, Ser. No. 544,930

Term of patent 7 years

Int. Cl. D21—01

U.S. Cl. D34—2 R

FIG. 1 is a front perspective view showing the facial and trunk and in general, the characteristics of the front portion of an elephant puppet showing our new design.

FIG. 2 is a rear perspective view showing the characteristics of the rear portion of the elephant puppet design of FIG. 1.

We claim:

The ornamental design for an elephant puppet, substantially as shown and described.
